Primary Examiner — Antoine D Davis(57) **CLAIM**

The ornamental design for a “fish tape guide,” as shown and described.

DESCRIPTION

FIG. 1 is a front perspective view of the fish tape guide;
FIG. 2 is a front view of the fish tape guide;
FIG. 3 is a rear view of the fish tape guide;
FIG. 4 is a left view of the fish tape guide;
FIG. 5 is a right view of the fish tape guide;
FIG. 6 is a top view of the fish tape guide;
FIG. 7 is a bottom view of the fish tape guide; and,
FIG. 8 is an environmental perspective view including the fish tape guide.

The broken lines shown in the drawings represent portions of the fish tape guide or environment that form no part of the claimed design.
